FOUNDATION GARMENT

Harry Jay Dubner, Forest Hills, N. Y.

Application January 19, 1944, Serial No. 518,844

3 Claims. (Cl. 2—43)

This invention relates to foundation garments of the type provided with a crotch portion.

Many women prefer that their foundation garments shall be provided with a crotch portion to assure proper support and holding of the torso throughout; others prefer a foundation garment having a "panty"-like portion in order to constitute a complete undergarment. With certain foundation garments and with certain wearers, a crotch portion is desirable to prevent the garment from creeping upwardly due to the action of the fatty tissues as the woman sits down and stands up. A particular advantage resides in combining a "panty" or crotch portion with an abbreviated foundation garment, such as a girdle, because such a garment is relatively small, compact and light in weight, and is easy to apply and remove; however a girdle has a greater tendency to slip upward than a complete foundation garment. Therefore the invention is shown in a girdle, but without being limited thereto.

In the instances mentioned, extreme discomfort is caused when the wearer sits or bends down, because excessive tension is created at the crotch portion. It is well known that the binding on the delicate tissues often results in considerable distress. Certain foundation garments have been provided with a back horizontally split along the waist line but these have only a relatively insignificant effect in avoiding binding at the crotch; in fact, these garments are made as a rule without a crotch portion, and they will relieve binding at the back and at the shoulder straps. The problem of relieving binding at the crotch cannot be solved by making the crotch portion of elastic material. Only where the entire girdle as well as the crotch portion are made of an open mesh elastic, is binding at the crotch relieved, but such elastic has insufficient strength to strongly embrace and confine the body of the wearer.

I have perceived that the binding at the crotch portion occurs due to the elongation of the rear curved line of the buttocks when the wearer is seated, and hence cannot be relieved by a back wall which is split at the waist line. I noted that the buttocks afford a powerful frictional restraining action on the garment resisting slippage of the garment which thus becomes virtually anchored at the buttocks. But this very thing appeared to offer an insuperable obstacle to relief at the crotch. If the back of the garment were split at the buttocks, so as to afford expansion for relief at the crotch, then the back portions at the split would not be able to slide back to

initial position when the wearer stood up; these portions, whether they overlapped each other or not, would stay in expanded position and would wrinkle up, show through the outer garment and cause discomfort at the buttocks.

5 It is, therefore, an object of the invention to provide a foundation garment having improved means for relieving binding at the crotch and for assuring that the garment shall expand and contract without restraint by the bulging tissues of the body.

10 Another object of the invention is the provision of improved means for relieving binding at the crotch and for limiting expansion of the back wall of a foundation garment in a vertical direction to suitably hold in the buttocks, the expansion being caused primarily by the buttocks to afford relief at the crotch.

15 Another object of the invention is to furnish a foundation garment having improved overlapping rear wall portions affording an opening for expansion to relieve binding at the crotch, the opening being elongated in the manner of a passage, the horizontal and vertical dimensions of which are so related to each other as to accomplish the several functions herein set forth.

20 Another object of the invention is to provide a foundation garment comprising a back wall including a crotch portion and an expansion opening in alignment therewith of a length less than the width of said wall and greater than the width of the crotch portion to afford limited vertical expansion resisted by a horizontal stress, preferably with the aid of horizontally acting elastic, the horizontal stress being distributed over a substantial portion of the elastic, and horizontal expansion of the wearer's body in seated position increasing the elastic stress so that the 25 garment has a proper restraining action on the body of the wearer.

25 Another object of the invention is the provision of improved simplified structure that is inexpensive to make.

30 Other objects and advantages of the invention will become apparent as the specification proceeds.

35 With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in rear elevation, drawn to scale, showing a girdle embodying the invention, the girdle being in flat condition.

Fig. 2 is a sectional view taken on line 2-2 of Fig. 1.

Fig. 3 is a view similar to that of Fig. 1 but showing the shape of the girdle as worn by a person in standing position.

Fig. 4 is a diagrammatic rear view of the girdle showing the shape thereof as worn by a person in sitting position.

Fig. 5 is a sectional view taken on line 5-5 of Fig. 4.

Fig. 6 is a sectional view taken on line 6-6 of Fig. 1.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 11 denotes a foundation garment such as a girdle embodying the invention. The same may be constructed of elastic or inelastic material for tightly embracing the body of the wearer. Preferably it includes a rear wall 12, a front wall 13 and side walls 14, the walls 12, 13 being made of inelastic material, and the side walls 14 being made of horizontally elastic fabric of any suitable kind. These walls may be continuously interconnected, but, if desired, the upper part of the front wall may have a vertical slide fastener closure (not shown) to facilitate the donning of the garment. The top edge 15 of the girdle lies at or near the waist line, and from there, the garment may increase in size downwardly, extending sufficiently far to completely enclose the buttocks, and, if preferred, the upper portions of the thighs. At its lower edge 16, a cut out 17 is formed in the front and rear walls, preferably somewhat larger in the rear than in the front wall. Secured to the edges of the cut out is a crotch member 18 of a soft, limp material, which is preferably non elastic. In the flattened condition of the garment in Fig. 1, this member 18 hangs down below the lower edge 16, but when the garment is worn, as in Fig. 3 the crotch member is filled out and hence assumes the position therein indicated. So far, the described structure is conventional.

At the region of the buttocks, the rear wall 12 is slit to produce an opening 20, which may be finished to prevent raveling of the fabric. This opening at 20 is covered by stitching a piece 22 at 23 below the slit and at 24 at each side of the piece 22. But the latter is not stitched at its upper end, whereby an opening 19 is produced between the back 12 and the piece 22. Accordingly, the opening 19 becomes a vertical passage defined by the lines of stitching 24 and by the element 22 overlapping its companion wall portion 25, the latter of which is integral with the rear wall. It will now be seen that the overlapping wall portions 22 and 24 are adapted for movement in opposite directions relative to each other for expansion and contraction effects, and in that sense the opening 19 may be regarded

as capable of expansion and contraction. When expansion occurs, the slit 22 opens up as shown, in which case the numeral 20 may be regarded as indicating the upper edge of the slit, and the wall portion 22 may be regarded as a continuation of the bottom portion of the back wall. Although various structural details have been mentioned, it will be appreciated that these can be varied, the object being to provide a suitable overlapped expandable contractile wall portion.

The overlapped wall portions 22, 25 lie at the region of the buttocks. With a woman whose height is about five feet two inches, the buttocks begin at about six inches below the waist line as indicated at 26, and attain their maximum bulk at about nine inches below the waist line as indicated at 27. It is thus seen that the overlapping wall portions preferably lie where the bulk of the buttocks is a maximum, and in fact the point 27 is about central in elevation relative to these portions. These overlapped portions have been brought as close as possible to the crotch portion, only enough material intervening to permit seaming of the elements 18 and 22.

It is to be noted that the horizontal length of the opening 19 is substantially greater than the width of the crotch portion and substantially less than the width of the back wall 12. In the woman of average torso of the height mentioned, the horizontal length of the opening 19 may be as much as eight inches and as little as five inches. The preferred length is about seven inches.

The overlapped portions are spaced substantially from the side walls 14 and their opening is in alignment with the crotch portion. The vertical length of the overlapped area as in Fig. 1 may be about three inches, which is preferably a minimum but may be as much as five inches.

There is an important relation between the horizontal and vertical dimensions of the overlapped area. In general, the greater the horizontal dimension, the greater must be the vertical dimension. The reason for this is that the greater the horizontal dimension the more the opportunity for vertical expansion; by increasing the vertical dimension, the opportunity for expansion is diminished.

The garment may be further understood by considering its precise action when worn. In Fig. 3, the garment is shown when worn by a person who is standing. In that case, there is some expansion due to relative movement between the overlapping wall portions 22, 25, as shown by the curved lines. If complete flatness is desired at the buttocks, this expansion is undesirable, but if a form fit is preferred, the buttocks should show some curvature, and in that case, this expansion is preferable. This expansion is controlled in the manner already indicated, by the vertical and horizontal dimensions of the opening or passage 19. The elastics 14 also play

a part; as shown they become stretched at the buttocks and increase the horizontal tension on the overlapped wall portions 22, 25, thus tending to resist expansion. The stresses that result are indicated by the arrows 28, 29, 30, causing

a distribution of the stresses throughout a substantial portion of the elastic, whereby the latter can more effectively resist undue expansion of the opening 19.

When the wearer sits down, the garment assumes the position shown in Figs. 4 and 5. Now

the expansion is about double that of Fig. 3, and may be more, thus relieving binding at the crotch portion. The portions 31 of the rear wall 12 are continuous past the wall portions 22, 25 and hence fully resist vertical expansion to confine parts of the buttocks as their curvature lengthens. Expansion, however, occurs laterally in the usual manner by horizontal stretching of the side walls 14 as shown, thereby increasing the horizontal tension on the wall portions 22, 25, tending to avoid undue expansion of the opening 19 and assuring proper restraint of the buttocks and causing the crotch portion to snugly engage the wearer. Ample horizontal tension is assured by distribution of the stresses as indicated by the arrows 28, 29, 30. The described action has the further advantage that the buttocks do not tend to slip out of the girdle, as heretofore, so that when the wearer stood up, the buttocks tended to push the girdle upward, out of place.

An essential characteristic is that with the teaching herein disclosed for the opening 19, the overlapping wall portions 22, 25 slide back to initial position which may be like that of Fig. 3, or like that of Fig. 1 for slender girls. This return to initial position is due in part to the fact that the horizontal length of the opening 19 is less than the width of the back wall 12, and in part to the depth of the opening 19, resulting in deformations which tend to right themselves, under the stresses created, and against the substantial resistance of the buttocks. Thus it is seen that the invention avoids binding at the crotch, especially in sitting position, and the structure avoids wrinkling, and is automatic, reliable and smooth in its action, and sufficiently flat and compact and located at a region sufficiently low so as to afford the results desired without showing any marks or irregularities through the dress of the wearer.

It is important to note that the expansion is not caused by crotch tension but rather by tension at the buttocks, whereby the crotch tension is always low and merely assisting the expansion. In fact the structure of the garment is such that the buttocks are fully restrained at their outer sides and rear, excepting only at a central region at the rear, at which a limited supporting expansion of the garment is permitted, above and lateral to the crotch member.

I claim:

1. A foundation garment having a wall adapted to continuously embrace the body of the wearer, a crotch member connected to said wall, the back of the garment having a horizontal slot in said wall immediately above the crotch member, a flexible sheet member at the buttocks connected along its bottom edge to said wall at the bottom

edge of the slot, the flexible member extending above the slot and being connected to the wall by generally vertical lines of connection located at the ends of the slot whereby the flexible member overlaps said wall, said wall being vertically expandable to a substantial degree at the slot to relieve tension on the crotch member in the sitting position of the wearer, and the vertical lines of connection being sufficient in length to cause the flexible member to limit the said expansion, the slot being wider than the crotch member but being substantially shorter than the width of the back of the garment as to provide vertically continuous sections at the back of the garment lateral to the slot for restraining adjacent parts of the buttocks and for producing tension such as to cause the overlapping portions of the garment to slip on each other to substantially reduce the expansion of the slot when the wearer stands up.

2. A device including a foundation adapted to embrace the body of a wearer, the garment having a portion whereby it is horizontally elastic, a crotch member, the garment having front and back walls having bottom cut outs in which the crotch member is connected thereto, the back wall having a horizontal slot immediately above the crotch member, and a member at the buttocks overlapping a portion of the back wall connected thereto at the bottom edge of the slot and extending upward therefrom, the overlapping member being connected to the back wall along generally vertical lines of substantial length at the ends of the slot, the overlapping member being otherwise free of the back wall so that when the wearer sits down, the buttocks engaged with the back wall below the slot cause expansion thereof and downward sliding movement of the overlapping member along the back wall to thus relieve tension on the crotch member, the slot being substantially wider than the latter and being substantially less in width than the back wall so that the overlapping member in co-operation with the vertical connections causes tension sufficient to resist the friction between the back wall and the overlapping member for returning the latter to initial position when the wearer stands up.

3. A device according to claim 2 wherein the length of the horizontal slot is not less than five inches nor more than eight inches, and the length of the vertical connections is not less than about three inches nor more than about five inches, these dimensions varying with the height of the wearer, and the dimension of the slot varying with the dimension of the said connections.

HARRY JAY DUBNER.
